UNITED STATES PATENT OFFICE.

MARTIN H. RICE, OF MOLINE, ILLINOIS.

TURNTABLE.

1,384,569.

Specification of Letters Patent. Patented July 12, 1921.

Application filed March 5, 1921. Serial No. 449,660.

To all whom it may concern:

Be it known that I, MARTIN H. RICE, a citizen of the United States, residing at Moline, in the county of Rock Island and

5 State of Illinois, have invented certain new and useful Improvements in Turntables, of which the following is a specification, reference being had to the accompanying drawing, forming a part thereof.

10 This invention relates more particularly to portable turn-tables for turning motor trucks or vehicles in connection with construction work such as road building, where materials such as sand, gravel, crushed stone and cement, have to be transported by trucks from the nearest railway or point of supply to the point of use, which shifts as the work progresses.

15 The main objects of the invention are to provide a turntable of simple, strong, durable and comparatively light construction, which can be easily transferred from place to place, and operated to turn loaded trucks around within the limits of their length for dumping; which requires no pit, excavation, permanent mounting or special foundation; which extends but a short distance above the ground and hence requires but little extra power to raise a loaded truck in running it upon the turn-table, and which admits of the use of standard shapes of steel in its construction; and generally to simplify and improve the construction and operation of turn-tables of this class.

20 30 35 It consists in the construction and organization of parts as hereinafter particularly described and pointed out in the claims.

In the accompanying drawing like characters designate the same parts in the several figures.

Figure 1 is a plan view of a portable turn-table embodying the invention, a part of one of the runways being broken away; Fig. 2 is a side elevation of the turn-table; Fig. 3 is an enlarged vertical cross section on the line 3-3, Fig. 1, of one of the trucks; Fig. 4 is an enlarged cross section on the line 4-4, Fig. 1, of the circular track, showing means of fastening the track to the runways; Fig. 5 is an enlarged cross section on the line 5-5, Fig. 1, of the circular track at one of the joints connecting the sections of which it is composed; Fig. 6 is a plan view of a portion of a modified construction 55 of the turn-table.

Referring to Figs. 1 and 2, the turn-table

comprises a circular track 1, which is mounted on and fastened to parallel runways 2.

The track, which may be conveniently 60 made of I-section or T-section, as shown in Figs. 3, 4 and 5, is preferably formed in two or more sections, which are rigidly connected with each other at the ends, as shown in Fig. 5, by splice plates 4.

65 The runners on which the track is mounted, may be made of wood shod with steel or metal plates 6, the runners being beveled or curved upwardly at the ends, as shown in Fig. 2, to facilitate hauling the turn-table 70 from place to place.

75 At the ends the runners are provided with hauling loops or bails 7, which may be pivotally connected therewith as shown, by the shoes 6 being bent backwardly over the tops of the runners and fastened thereto.

The track is fastened to the runners by any suitable means, for example, as shown in Fig. 4, by angle plates 9 bolted to opposite sides of the rail web and through the 80 runners.

A platform comprising rigidly connected parallel runways 11, is rotatably mounted on the circular track 1.

85 The runways are preferably made as shown, of steel or metal channel bars, the upwardly extending flanges 12 of which serve to guide and retain the wheels of a vehicle in place on the turn-table. As equivalents of the integral channel bars, flat plates 90 having angle bars fastened to their edges to form wheel guiding and retaining flanges, may obviously be used in the construction of the runways.

95 The runways may be rigidly connected and held in the proper relation to each other, as for example, by angle bar cross pieces 13, riveted or bolted to plates 14, which are in turn riveted or bolted to the under side of the runways 11.

100 105 110 To hold the platform in place on the circular track and to facilitate its rotation with a load thereon, without unduly elevating the runways 11 above the ground or surface on which the turn-table rests, the runways are suspended by truck frames from the axles of flanged wheels 16, adapted to traverse the circular track 1. The truck frames preferably consists as shown, of angle bars 18, riveted or bolted to the under side of the runways 11 obliquely thereto, and of wheel hangers 19, mounted on and extending up-

- wardly from the bars 18. The bars 18 are preferably curved to correspond with the curvature of the circular track 1, on opposite sides of which they are arranged in 5 pairs parallel with each other adjacent the ends of the runways. The hangers 19 are preferably made as shown in Fig. 3, of standard angle bars like or similar in section to that of the bars 18, to which they are riveted or bolted. The wheels 16 are mounted on pins or axles 21, passing through and carried by the hangers radially with relation to the circular track and the center of the rotatable platform.
- 10 15 Spacing washers 23, are placed on the axles between the hangers and the truck wheels, as shown in Fig. 3, and anti-friction rollers 24 are preferably interposed between the axles and the bores of the wheels.
- 20 25 At their ends the runways 11 are provided with vertically swinging leaves or approaches 26, hinged or pivoted thereto, as shown in Figs. 1 and 2, and formed with upwardly projecting guide flanges, diverging outwardly from the flanges 12 of the runways.

- The hinged leaves or approaches 26 are preferably connected with the runways 11 by springs 29, which tend to hold them 30 either in their lowered position, as shown by full lines in Fig. 2, or in their elevated position against the wheels of a motor truck or vehicle on the turn-table, as indicated by dotted lines in the same figure.
- 35 40 One or both of the hinged leaves or approaches 26 at each end of the platform, is provided with a holder 31, in which a handle bar 32, indicated by dotted lines in Fig. 1, is removably fitted, to facilitate turning the platform with a loaded truck or vehicle thereon.

- In connection with a track 1, of I-section, having a flat head as shown in Fig. 3, the treads of the truck wheels are preferably 45 crowned, to reduce friction. With a track of T-section having a crowned or rounded head, truck wheels having flat treads may be used.

- The truck wheels are preferably covered 50 by housings 34, fastened to the hangers 19, to protect them from sand, etc., which may fall on them from loaded trucks on the turn-table, and which might otherwise interfere with their free action and get into and cut 55 their bearings.

- In the construction shown in Figs. 1 and 2, each runway 11 is supported at each end by two truck wheels, one on each side thereof.

- Referring to Fig. 6, showing a modification, each runway 11 is provided at each end 60 with a single truck wheel 16, preferably located on the outer side thereof, and one of the angle bars 18' is extended to connect the runways with each other, thereby taking the 65 place of and dispensing with the separate

cross pieces 13 shown in Fig. 1. The other angle bars 18'' of the truck frames may terminate at or adjacent to the inner sides of the runways 11 to which they are riveted or bolted, as shown, or if desired, may be extended to form an additional cross connection between the runways, like the bars 18'. In other respects, the design and construction of the turn-table may be like or similar to that shown in Figs. 1 and 2.

70 Constructed according to either design, a comparatively light turn-table may be produced, which can be easily operated and hauled with a truck or tractor from place to place as the work progresses, and which with 80 the exception of the truck wheels, may be completely built with standard shapes of steel, thereby greatly facilitating its construction and materially reducing its cost.

85 Various modifications other than those particularly mentioned, may be made in the construction and arrangement of parts of the turn-table, without departing from the principle and scope of the invention as defined in the following claims.

90 I claim:

1. In a turn-table the combination of runners, a circular track mounted on the runners, parallel runways, and truck wheels connected with the runways alongside thereof and extending above their lower sides in position to run on the track and suspend the runways close to the track.

95 2. In a turn-table the combination of runners, a circular track mounted thereon, connected parallel runways, truck wheels adapted to run on the track, and hangers suspending the runways from the wheels, whose axes are located above the lower sides of the runways and radial to the track.

10 3. In a turn-table the combination of runners, a circular track mounted thereon, connected parallel runways, truck frames comprising angle bar cross pieces fastened to the under sides of the runways, wheel hangers mounted on said cross pieces and extending upwardly therefrom, and wheels suspending the runways from the hangers and guided on the track.

11 4. In a turn-table the combination of runners, a circular track mounted thereon, connected parallel runways, truck frames consisting of angle bar cross pieces fastened to the under sides of the runways and projecting therefrom at an oblique angle thereto, angle bar hangers fastened to the upper sides of the cross pieces and extending upwardly therefrom, wheel axles mounted in said hangers radially to the circular track, and wheels mounted on said axles and guided on 11 said track.

12 5. In a turn-table the combination of runners, a circular track fixed thereon, parallel runways provided with upwardly projecting longitudinal guide flanges, trucks provided 11

- with wheels which are guided on the track and from which the runways are suspended with their lower sides close to the track and vertically swinging leaf-approaches hinged 5 to the ends of the runways and having upwardly projecting guide flanges diverging outwardly from the flanges of the runways.
6. In a turn-table the combination of parallel runners, a circular track mounted 20 on and fastened to the runners, connected parallel vehicle-runways, and trucks on which the runways are suspended with their lower sides close to the track, provided with flanged wheels adapted to follow and run on 25 the track.
7. In a turn-table the combination of parallel runners, a circular track fixed thereon, connected parallel runways, trucks connected with the runways and provided alongside thereof with wheels which are guided on the track and from which the runways are suspended with their lower sides close 10 to the track, vertically swinging leaf-approaches hinged to the ends of the runways, and a handle bar holder on one of the leaf-approaches.
8. In a turn-table the combination of parallel runners, a circular I-bar track fixedly mounted thereon and having a flat head, connected parallel vehicle-runways, 30 and trucks on which the runways are mounted, provided with flanged wheels having crowned treads adapted to follow and run upon the circular track.
- In witness whereof I hereto affix my signature.

MARTIN H. RICE.
